UNITED STATES PATENT OFFICE.

JOHN D. LEEN, OF BANGOR, MAINE, ASSIGNOR OF ONE-HALF TO SAMUEL STERNS AND EZRA L. STERNS, OF BANGOR, MAINE.

NAIL-CABINET.

No. 895,095.

Specification of Letters Patent.

Patented Aug. 4, 1908.

Application filed December 20, 1907. Serial No. 407,393.

To all whom it may concern:

Be it known that I, JOHN D. LEEN, a citizen of the United States, residing at Bangor, in the county of Penobscot and State of Maine, have invented a new and useful Improvement in Nail-Cabinets, of which the following is a specification.

This invention is an improvement upon the nail cabinet for which Letters Patent 10 were granted to me February 18, 1902, Serial Number 693,525.

The invention consists in providing the cabinet with means operated from without the cabinet for checking delivery of nails 15 from the front compartment, and permitting them to be drawn from a rear compartment while the first compartment is full.

The invention also includes a device for filling the cabinet.

20 In the accompanying drawings—Figure 1 is a perspective view of my cabinet. Fig. 2 is a vertical section therethrough taken from back to front. Fig. 3 is a vertical section taken through the ends of the cabinet. Fig. 25 4 is a detail perspective view of the nail filling device.

In these drawings A represents the cabinet casing which is provided with the nail holding drawers B and the retaining needles C, 30 these parts being fully shown and described in the patent above referred to. The casing A is divided by a central partition A¹ into two separate parts each of which is provided with its own drawer B. Each side of the 35 cabinet A is further subdivided by a vertical partition D which stops short the inclined bottom A² of the cabinet.

In my patented construction the partitions which correspond to the partitions D 40 of the present construction were moved vertically in order to open or close communication between the rear compartments and the drawers B. In the present construction the partitions when once adjusted 45 remain in their adjusted position. Each side of the cabinet therefore consists of a front and a rear compartment separated by one of the partitions, and communicating beneath the lower edge of said partition. 50 I secure in each front compartment a V-shaped wire check E which attachment is angled midway its ends so that the free end portions set at right angles to the apex, and these free end portions rest within the front 55 compartment being passed through suitable

openings A³, the apex portion normally extending downwardly against the front face of the cabinet, and the free end portions, which form a check for the nails placed in said front compartment, extending across 60 the compartment in a horizontal plane. These check frames are held in this position by rotatable hooks F which are engaged by the apices of the check frames. When the nails have been withdrawn from the rear compartment and it is desired to remove them from the front compartments it is only necessary to turn up the hooks F and the inner free end portions of the check frames will be swung downwardly by weight 65 of the nails resting thereon, and the outer portion will swing upwardly into a horizontal plane as shown in Fig. 2 by the dotted lines. The nails will then be fed from the front compartment. It will be understood that 70 when nails are placed in such a cabinet they are matted or intermingled, and consequently the inwardly extending free end portions of the wire frame are sufficient to uphold practically the entire mass. 75

In order to fill the compartments conveniently I employ a box G which has one end H pivotally connected midway its two sides to the sides of the box G. To prevent swinging movement of this end gate H a cross bar H¹ is placed on the box and a button J is pivotally mounted upon said cross bar. When turned at right angles to the cross bar the button J bears against the end H upon its pivotal point and holds its lower edge portion firmly against that end of the box bottom. When the box G has been filled by emptying a nail keg therein it is tilted with the gate end resting on the top of the cabinet A, and the button J turns parallel to the cross bar H¹, thus allowing the weight of the nails pressing against the lower portion of said gate to swing it downwardly, and the upper portion of the gate swinging inwardly and striking the cross bar H¹. The nails are therefore easily discharged into the proper compartment of the cabinet. 90 95 100

Having thus fully described my invention, what I claim as new and desire to secure by Letters Patent is:—

1. The combination with a nail cabinet having vertically extending compartments, a V-shaped check frame angled and loosely carried by the front wall of the cabinet, the 110

free portions of said frame normally extending transversely into the front compartment, and a hook adapted to engage the apex of the frame, said hook being upon the 5 exterior of the cabinet.

2. The combination with a nail cabinet having front and rear compartments, said compartments communicating at their lower ends, the cabinet having an inclined 10 bottom, an angled frame extending through the front of the cabinet, said frame being

pivottally mounted at the angle of the frame in the front wall of said cabinet, and a fastening device adapted to normally hold the exterior portion of the frame parallel to the 15 vertical front of the cabinet, as and for the purpose set forth.

JOHN D. LEEN.
